CLAIM

The ornamental design for a footwear outsole, as shown and described.

DESCRIPTION

FIG. 1 is a bottom perspective view of a footwear outsole showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines showing the remainder of the shoe sole throughout the views illustrate the portion of the design that forms no part of the claim.
